COMBINATION UMBRELLA NOTCH FERRULE

Philip S. Sobotka, Baltimore, Md.

Application October 12, 1945, Serial No. 621,985

2 Claims. (Cl. 135—36)

1

This invention pertains to umbrellas and more particularly to a combined notch and ferrule for same.

Some arrangements employed for holding the cover of an umbrella in place require the use of a notch member, rosette washer and a ferrule and sewing to keep it in place. Sometimes the ferrule at the end of the stick is glued on. The disadvantages of this construction is that it loosens and becomes lost and allows the cover to come off or get injured in addition to allowing rain water to enter the end of the umbrella and stick and rot same.

It is an object of this invention, to provide a new and improved ferrule unit that will be combined with the notch and perform additional functions not secured in the use of them separately.

It is an additional object of the invention, to provide a new and improved ferrule unit that will avoid one or more of the disadvantages and limitations of the prior art.

Another object of the present invention is to provide a new and improved ferrule unit that will secure itself firmly to the stick of an umbrella and hold the cover properly in place.

An additional object of this invention is to provide a new and improved ferrule notch unit that will be economical to make and install.

Other objects will become apparent as the invention is more fully set forth.

In a particular form, illustrated as an example of this invention in the drawings:

Figure 1 is a view of an umbrella in closed position, embodying this invention.

Figure 2 is an enlarged end view of Figure 1.

Figure 3 is an enlarged view of the combined notch and ferrule showing the umbrella ribs, cover and rosette in section.

Figure 4 is a sectional view taken along line 4—4 of Figure 3.

Figure 5 is an end view of the sleeve, and

Figure 6 is a side elevation, partly in section, of the sleeve shown in Figure 5.

Similar reference characters refer to similar parts throughout the drawings.

In the structure shown, an umbrella 1 is shown fitted with a handle 8, and an umbrella stick 10 is formed with a slightly tapered end portion 11.

On this portion 11 is slid a tapered ferruled thimble 12 which includes an integral rib notch ring 13 of conventional form for pivotally holding the ribs 14. The cover 15 is sewed to the ribs in the ordinary manner with its central portion 16 lapped over and open to slip over the ferrule 55

2

thimble 12 and rest on its notch ring 13. A raised ring shoulder 17 is integrally formed peripherally around the body of the ferrule thimble 12 and spaced sufficiently from the upper surface 18 of the notch ring 13 to allow a hollow cylindrical sleeve 19 to fit and encompass it tightly and clamp the cover central portion 16. The section of the shoulder 17 is as indicated, its under surface 21 being flattened while its upper surface 22 is bevelled, while its depth is not over one-sixteenth of an inch for ferrule thimble used on an ordinary umbrella. The normal thickness of the walls of the thimble is about three-sixteenths of an inch for a conventional plastic suitable for the device. The end portion 23 of the thimble termed the cap is closed-in and rounded. The interior surface of the thimble is preferably tapered to fit on to the tapered stick 10 tightly when pushed on. The thimble may be pinned on the stick in the regular manner if desired. The exterior is generally straight. The sleeve 19 is bevelled interiorly at one end 24 to conform with the bevel 22, so that when pushed on, the sleeve will stretch resiliently as the sleeve passes over the shoulder 17 and resiliently settles in the spacing provided for it, against the surface 21. The wall under this surface is compressed by the sleeve 19 when in place as it is slightly less in diameter and clamps the stick more tightly so it cannot be removed. At the same time the rosette 26 and cover portion 16 are secured and held over the notch ring 13. The unit combines parts usually separated into three distinct elements, into one, and adds the sleeve 19 for making it stronger and more effective, in addition to eliminating the tieing and stitching formerly required. The cover also is held tightly in place and is kept taut and leak proof at the end and strengthens the entire umbrella in a more substantial manner than has formerly been possible.

While but one general form of the invention is shown in the drawings and described in the specifications, it is not desired to limit this application for patent to this particular form or in any other way otherwise than limited by the scope thereof, as it is appreciated that other forms of construction could be made that would use the same principles and come within the scope of the appended claims.

Having thus described the invention, what is claimed is:

1. A combination thimble and ferrule unit of the class described to be used on umbrellas to fasten the cover, ribs and rosette to the stick without the aid of sewing and comprising a hol-

low ferrule closed at one end and having a notch portion at the other end to support the umbrella ribs thereon, a raised shoulder on the outer surface of said ferrule near the closed end thereof and a straight face running from said shoulder to the notch, a resilient sleeve adapted to stretch over said raised shoulder and to resiliently settle to its original size to clamp tightly against said straight face.

2. A combined notch and ferrule unit for attachment to an umbrella stick and for holding the cover and ferrule without sewing and gluing, said ferrule being closed at one end to prevent weather from entering, said ferrule having a notch portion integrally connected thereto for receiving and holding umbrella ribs, said ferrule having a raised portion near the closed end, the

balance of the ferrule being straight between the notch and said raised portion, and a sleeve adapted to stretch by sliding over said raised portion and to return to its normal size to tightly grip the said straight face between the notch and raised portion.
